ATTORNEY

UNITED STATES PATENT OFFICE.

GUST R. NYQUIST, OF FRESNO, CALIFORNIA.

SPRING.

1,336,314.

Specification of Letters Patent.

Patented Apr. 6, 1920.

Application filed May 14, 1917. Serial No. 168,507.

To all whom it may concern:

Be it known that I, GUST R. NYQUIST, a citizen of the United States, residing at Fresno, in the county of Fresno and State 5 of California, have invented certain new and useful Improvements in Springs, of which the following is a specification.

This invention relates to new and useful improvements in an elliptic spring for 10 vehicles and the like, and the principal object of the invention is to reduce the friction between the parts and to reduce the amount of metal necessary to form the spring.

In an ordinary leaf spring the steel in 15 the longitudinal center only acts as bulk and has no other useful function. The bottom part of the leaf has tension while the top of the leaf compresses, while the steel in the center of the leaf binds the top and bottom 20 together and keeps them from performing their full function. I overcome this defect by dividing the leaves of the spring at the centers and splitting them longitudinally and forming the entire spring of one piece 25 of metal bent on itself to form the split leaves, or by forming a shoulder on one leaf against which the top half of the adjacent leaf bears. Thus the lower half of each leaf has tension, while the upper half 30 has compression.

The invention also consists in certain other features of construction and in the combination and arrangement of the several parts, to be hereinafter fully described, 35 illustrated in the accompanying drawings and specifically pointed out in the appended claims.

In describing my invention in detail, reference will be had to the accompanying 40 drawings, wherein like characters denote like or corresponding parts throughout the several views, and in which:—

Figure 1 is a front view of the spring with parts in section and parts broken away,

Fig. 2 is a like view of part of a spring with parts in section and showing a modification,

Fig. 3 is a perspective view of one of the leaves shown in Fig. 1, and

Fig. 4 is a like view of the top leaf of Fig. 2.

As shown in these figures I divide the leaves of the spring at their centers and clamp them together by means of the top 55 clamp or bracket 1 having the wings 2 and

the central projection 3 extending into the space between the inner ends of the leaves. This projection has a hole 4 passing through the same, and a recess therein communicating with the whole four to receive the screw 60 threaded ends of the clip 5. This clip holds the wedge member 6 in engagement with the bottom part 7 of the lowermost leaf which is not divided at its center as are the other leaves. 8 and 9 represent two other 65 clips passing through holes in the wings 2 of the bracket 1 and engaging the leaves of the spring so as to clamp them on the bracket as shown in Fig. 1. In this way the leaves are securely held in position as 70 the three clips with the bracket and wedge member set up a clamping action on the leaves of the spring.

As shown in Fig. 1, I form each part of each leaf of a piece of metal bent on itself 75 at its outer edge so as to form a half leaf 10 having a horizontal slit 11 therein extended from a point adjacent its outer end through its inner end, thus the leaf is divided into an upper part 12 and a lower part 13. This 80 lower part 13 at its inner end is provided with a thickened portion 14 forming a shoulder where it joins the rest of the bottom part and the upper part of the next leaf is of slightly less length than the bottom 85 part and engages the shoulder. A shoulder 15 is formed in the bracket 1 to receive the upper part of the first leaf. The lower half of the bottom leaf extends from end to end of the spring and is not divided 90 centrally as are the other leaves and this lower part is clamped between the member 6 and the bracket 1 as before stated. Thus the adjacent ends of the two parts of the leaves are clamped together to form a 95 complete spring and by reason of the split leaves a greater power is given to the spring as the tendency of the metal of the spring to assume a straight position will cause the upper half of each leaf to have 100 a compression action, while the lower half has tension as before stated. The clamping clips 8 and 9 have shoulders formed thereon which engage the bracket so as to allow a working fit for the leaves. The upper 105 half of each leaf is compressed against the shoulder of the leaf above.

In the construction shown in Figs. 2 and 4, I form the leaves from one piece of metal instead of forming shoulders as in Figs. 1 110

and 3, an on the upper leaf, I form a projection 16, which engages in a groove 17 in the bracket 1' to hold the upper leaf against movement in relation to the bracket. In 5 this construction the metal beginning at the projection 16 is carried forward to form the upper half of the first leaf, then doubled on itself forming the lower half thereof, then bent back to form the upper half of the sec- 10 ond leaf and so on to the bottom half of the last leaf. It is then carried between the clamps and is doubled upon itself to form the leaves on the other side of the spring. In other respects, this construction is simi- 15 lar to that first described and the action of this spring is also similar.

It is thought from the foregoing that the advantages and novel features of my invention will be readily apparent.

20 I desire it to be understood that I may make slight changes in the construction and in the combination and arrangement of the several parts, provided that such changes fall within the scope of the appended 25 claims.

I claim as my invention:

1. A spring comprising a plurality of leaves, each leaf being folded to form super- 30 posed layers, and each leaf having a shoulder thereon engaging with a part on the adja- cent leaf.

2. A spring comprising a pair of groups of leaf springs, each leaf thereof being folded to form superposed layers, and 35 clamping means for holding the two groups.

3. A spring comprising a pair of groups of leaf springs, each leaf being folded to form superposed layers, and clamping means for holding the groups and the parts of each 40 leaf spring together.

4. A spring comprising a pair of groups of leaf springs, each leaf of each group being folded to form superposed layers, clamping means for holding the groups to-

gether, and shoulders on said means for en- 45 gaging with the top leaf.

5. A spring comprising a plurality of superposed leaves, said leaves arranged in a pair of groups, a leaf extending from one pair to the other, and clamping means for 50 holding said leaf and groups together.

6. A leaf spring having its superposed leaves formed from a single strip of metal, said leaves arranged in a pair of groups, 55 a portion of said strip joining the groups, and clamping means for holding said portion of said strip and said groups together.

7. A leaf spring having its superposed leaves formed from a single strip of metal, said leaves arranged in a pair of groups, a 60 portion of said strip joining the groups, clamping means for holding said portion of said strip and said groups together, and a shoulder formed upon one leaf and engaging with the clamping means.

8. A spring comprising a plurality of superposed leaves arranged in groups formed by folding a single strip of metal.

9. A spring comprising a pair of groups of leaf springs, a plate associated with the 70 tops of said groups, said plate having a projection extending between the groups, and clips associated with said projection and the ends of said plate for clamping the plate to said groups.

10. A spring comprising a plurality of leaves each leaf being folded to form super- 80 posed layers, and each leaf having a depending shoulder adapted for engagement with the lowermost layer of the adjacent leaf.

In testimony whereof I affix my signature in presence of two witnesses.

GUST R. NYQUIST.
